US00D532637S

(12) **United States Design Patent** (10) Patent No.: **US D532,637 S**
Bassett et al. (45) Date of Patent: **** Nov. 28, 2006**

(54) **LIQUID DISPENSER BODY**
(75) Inventors: **Wade M. Bassett**, Albia, IA (US); **Lisa L. Bassett**, Albia, IA (US)
(73) Assignee: **MBHD, LLC**, Albia, IA (US)
(**) Term: **14 Years**
(21) Appl. No.: **29/219,517**
(22) Filed: **Dec. 17, 2004**
(51) LOC (8) Cl. **06-11**
(52) U.S. Cl. **D6/545**
(58) Field of Classification Search **D6/545, D6/542; D9/520, 521, 689, 693; 222/173, 222/181.1, 413; 4/227.6**

See application file for complete search history.
